UNITED STATES PATENT OFFICE

100,713

DESIGN FOR A DOOR FOR A HEATER

Luke O. Morin, Jr., Chattanooga, Tenn.

Application June 19, 1936, Serial No. 63,398

Term of patent 14 years

To all whom it may concern:

Be it known that I, Luke O. Morin, Jr., a citizen of the United States, residing at Chattanooga, in the county of Hamilton and State of Tennessee, have invented a new, original, and ornamental Design for a Door for a Heater, of which the following is a specification, reference being had to the accompanying drawing, forming part thereof, in which

Figure 1 is a front elevational view of a door for a heater, showing my new design.

Figure 2 is a top plan view; and

Figure 3 is a sectional view, taken on the line 3—3 of Figure 1.

I claim:—

The ornamental design for a door for a heater, as shown.

LUKE O. MORIN, JR.
